United States Patent Office.

KASSON FRAZER, OF SYRACUSE, NEW YORK.

Letters Patent No. 81,993, dated September 8, 1868.

IMPROVED WEDGE-BUCKLE FOR HARNESS.

The Schedule referred to in these Letters Patent and making part of the same.

TO ALL WHOM IT MAY CONCERN:

Be it known that I, KASSON FRAZER, of the city of Syracuse, in the county of Onondaga, and State of New York, have invented certain new and useful Improvements in Wedge-Buckles for Harness; and I do hereby declare that the following is a full, clear, and exact description of the same, reference being had to the annexed drawings, which form a part of this specification, wherein—

Figure 1 represents a perspective view of the buckle, with hames-tug and a trace in their places.

Figure 2, a perspective view of the wedge and tongue.

Figure 3, a longitudinal sectional view, showing the connection of the parts, and with the tongue inserted in the trace.

The letters used indicate corresponding parts whenever they occur.

All the parts may be made of malleable iron, wrought iron, steel, or other suitable metal for the purpose.

I make the buckle-frame A of proper size and shape, in the general form indicated by the drawings, and with convenient loops, *a b c*, for various straps, and with a loop, *d*, for the hames-tug.

At the bottom of the buckle-frame A, and forming a part thereof, I make the bed-piece B, with as lot, *s*, for the guard of the tongue to play in, as hereinafter more particularly described.

As a part of the buckle-frame A, I make the cap *e* with supports, *ff*, on the sides, so arranged that such cap, in connection with the bed-piece B, will form an angular box, *x*, through which the trace passes, and in which the wedge will operate, as hereinafter described.

The cap *e* also has a slot or opening, *g*, into which the end of the tongue may play, and enables it to move to the left when the draught is applied.

I make the wedge W in the general form, as indicated by the drawings, with bearing-surfaces, *h h*, on the under side thereof, long enough to avoid excessive local friction, which produces a wedge-form and action, and such wedge will be of proper size to readily move backwards and forwards on the bed-piece B.

The wedge W also has a transverse slot, *i*, to form an opening for the journal *o* of the tongue to operate in, and should be made with nibs, *n n*, to clinch down upon said journal and keep it in place, and thus fasten the tongue to the wedge.

In the wedge W, I also make a hole, *m*, for the tongue to pass through, and with a stop, *r*, to keep the tongue from dropping down too far, and wholly falling out of the hole.

The tongue T is made with a journal, *o*, shank, *p*, and guard, *q*, and with a tongue proper, *t*, in ordinary form, substantially as shown in the drawings.

The end of the guard *q* should be made in a T-shape, long enough transversely to cover the slot *s* in the bed-piece, and enable it to move backwards and forwards on the under side of such bed-piece.

The different parts being made as aforesaid, the tongue is put in place, and the nibs *n n*, to close down upon the journal *o*, are clinched, substantially in the manner described, or the journal *o* may be held in any other ordinary way. In this manner the tongue T and wedge W are united by a joint, but a spring might be used instead of the shank and journal, to serve the purpose of a joint in operating the tongue. I consider the above device, however, much preferable.

The wedge and tongue thus combined are then inserted in the angular box *x* of the frame A, with the end of the tongue *t* ready to play in the slot *g*, and the guard *q* in the slot *s*, and with the bearing-surfaces *h h* of the wedge ready to move upon the bed-piece B. This bed-piece should be made as long as possible, so that the wedge may have a longer bearing thereon, which will also help to render or move the trace more easily, and avoid excessive local compression on the trace.

The edge of the bed-piece B, next to the loop *d*, should be brought up near enough to said loop to fairly allow the leather of the hames-tug H to pass through and fill up the space, which being done, the wedge and tongue are prevented from dropping out by the guard *q* being confined to the slot *s*.

In preparing the-buckle for use, the guard *q* should of course be thus inserted before the hames-tug is applied.

The trace D being inserted at the small end of the angular box *x*, (at the left, as shown in the drawings,)

and moved to the right, naturally shoves the wedge forward, and as the end of the trace strikes the tongue proper, *t*, that is thrown backwards and downwards, and the passage of the trace is thus rendered comparatively free from obstruction. Then, when the trace is drawn back, the hole will ordinarily catch the point of the tongue proper, *t*, or it may readily be done by pressing the guard *q*. As soon as the tongue proper passes into one of the holes, *y y*, in the trace, the natural effect of drawing upon the trace in the proper direction, will be to bring the wedge and tongue fully within the angular box *x*, and a powerful compression then takes place upon the leather, proportioned in degree to the draught, by the combined influence of the cap *e*, the bed-piece *B*, and the wedge *W* in resisting such draught. What I claim as my invention, and desire to secure by Letters Patent, is—

1. The wedge *W*, when made with the transverse slot *i*; hole *m*, and stop *r*; the tongue *T*, made with the journal *o*, shank *p*, and guard *q*, each substantially in the form and for the purposes described.
2. And I also claim the same parts, in combination with each other, when connected by a joint, and forming a wedge and tongue, substantially in the manner and for the purposes described.
3. I further claim the wedge *W* and tongue *T*, when made as aforesaid, in combination with the buckle-frame *A*, having an angular box, *x*, as described, all operating in the manner and for the purposes substantially as above set forth.

KASSON FRAZER.
